(57) **CLAIM**

The ornamental design for the case harness, as shown and described.

DESCRIPTION

FIG. 1 is a front isometric view showing my new design for a case harness;

FIG. 2 is an isometric back view of the case harness;

FIG. 3 is a front view of the case harness;

FIG. 4 is a right side view of the case harness, the left side being a mirror image thereof;

FIG. 5 is a bottom view of the case harness, the top view being the same;

FIG. 6 is a back view of the case harness;

FIG. 7 is a back view of the case harness with the broken lines showing the environment of its use; and,

FIG. 8 is a front view of the case harness with the broken lines showing the environment of its use.

The broken lines showing stitching and an electronic device are for the purposes of illustrating environment and form no part of the claimed design.
